UNITED STATES PATENT OFFICE.

VINCENT TANASSO, OF NEW YORK, N. Y.

DESIGN FOR A NOSE BRIDGE FOR EYEGLASS FRAMES.

Application filed February 8, 1928. Serial No. 25,273. Term of patent 14 years.

To all whom it may concern:

Be it known that I, VINCENT TANASSO, a citizen of the United States, residing at New York, in the county of New York and State of New York, have invented a new and original Design for Nose Bridges for Eyeglass Frames, of which the following is a specification, reference being had to the accompanying drawings, forming part hereof.

In said drawings, Figure 1 is a front elevation of the nose bridge as mounted to the lens rims of eye-glass frames; Figure 2 is a front elevation of the nose bridge alone; and Figure 3 is a top edge view of the nose bridge as mounted to the lens rims of eye-glass frames; said views showing my new design which comprises curvilinear side members having intermediate their ends lateral abut-

ments to space said members from the eyeglass lens rims, said side members lying in the plane of said lens rims, and a bridge portion extending between the upper ends of said side members, said bridge portion comprising a flat center member upwardly off-set relative to the ends of said side members and forwardly off-set in a plane parallel to the plane of said lens rims, and having its respective ends joined to the upper ends of said side members by arcuate portions; said side members and bridge portion having outwardly facing flat surfaces.

I claim:

The ornamental design for a nose bridge for eyeglass frames as shown and described.

Dated this 1st day of February, 1928.

VINCENT TANASSO.
